UNITED STATES PATENT OFFICE.

WARNER R. BUXTON, OF LONGMEADOW, MASSACHUSETTS, ASSIGNOR TO BUXTON,
INCORPORATED, A CORPORATION OF MASSACHUSETTS.

CASE FOR KEYS AND THE LIKE.

Application filed September 12, 1921. Serial No. 500,060.

To all whom it may concern:

Be it known that I, WARNER R. BUXTON, a citizen of the United States, residing at Longmeadow, in the county of Hampden 5 and State of Massachusetts, have invented new and useful Improvements in Cases for Keys and the like, of which the following is a specification.

This invention relates to improvements in 10 cases for keys and the like and, more particularly, to such cases wherein the keys are supported in snap hooks and these hooks are pivotally supported from the case and arranged to swing out of the case along a 15 substantially definite arc-like path. One example of the general type of key case, with which this invention is concerned, is shown in U. S. Letters Patent, No. 1,261,692, granted to me on April 2, 1918.

20 This invention is particularly concerned with the provision of means, in a key case of the type described, whereby the key-supporting snap hooks may not only swing in the desired arc-like path into and out of the 25 case but may also turn about an axis substantially at right angles to that about which they swing.

According to this feature of the invention, the hooks are virtually swivelled, as 30 well as pivoted, and can turn with the key when the latter is turned in the lock. Ordinarily, the case is held in the palm of the hand with two or three fingers while the key is held between the thumb and first finger 35 and, in turning the key in the lock, a side strain is applied to the snap hook which tends to open it or distort it. Due to this condition, specially constructed hooks have been provided for key cases to prevent 40 the keys from coming off the snap hooks when thus placed under strain. With the provision for the swivelling movement, the hook will turn relatively to the case, under such conditions, and the undesirable side 45 strains usually imposed are avoided. Also the hooks may swivel while enclosed within the case to enable the keys to pack down into small compass.

The object of this invention is to provide 50 an improved hook for the purpose set forth and one which is of simple construction and comparatively inexpensive to manufacture.

Other features of the invention will appear in the following description and in the

illustrative embodiment of the invention in 55 the accompanying drawings, in which:

Fig. 1 is an elevational view of a key case embodying the invention, the flaps of the case being shown in open position;

Fig. 2 is a similar view of the key case 60 with the flaps closed;

Fig. 3 is an enlarged fragmentary cross sectional view taken on the line 3—3 of Fig. 1;

Figs. 4, 5 and 6 are front elevational, side 65 elevational, and top plan views, respectively, of the snap hook; and

Fig. 7 is a fragmentary perspective view of the hook supporting member.

Referring to these drawings, the case 70 forming member may be variously constructed as desired, but preferably, as shown, it is substantially like that of my prior patent, such member being preferably formed from a strip of flexible material, 75 such as leather and the like, and having a back 10 and two flaps 11 foldable in overlapping relation over the back. These flaps 11 may be held together in overlapping relation by any suitable means, such as the interengagable male and female fasteners shown at 12 and 13 respectively.

The back 10 is suitably provided along its upper edge with a pivotal support for a series of snap hooks h . Preferably, although not necessarily, this support is afforded by a separate member, such as 14, which I also term a key holder and which is adapted to be secured to the back 10 by some suitable means, of which the eyelets 15 are 80 an exemplification. The member 14, preferably of thin sheet metal, is also provided with a series of sockets 16 in which are received suitably formed heads 17 on the upper ends of the shanks 18 of the snap hooks 95 h . These heads 17 are arranged to so engage the sockets 16 that the hooks may not only swing relatively to the support 14 in a substantially definite arc-like path but may also swivel about an axis at right angles to 100 that about which they turn and this swivelling may occur at any of the many positions which the hooks may assume during this swinging movement.

According to the broad features of the invention the precise location of the swivel connection is not important. However, for convenience and simplicity I prefer to in-

corporate the swivel connection with the pivotal connection, although this arrangement may be readily varied and still embody my invention. Likewise the precise way in which the sockets 16 are constructed and interengage with the heads 17 for cooperative action is immaterial so far as the broader aspects of the invention are concerned.

10 As an illustrative example of one suitable and advantageous way of accomplishing the desired results, the sockets 16 are formed by rolling up one end of the support 14 into hollow cylindrical form, such end having 15 been previously provided at a series of longitudinally spaced points with slots, such as 19, whereby a series of axially-aligned and axially spaced hollow cylindrical members 20 are formed. Each member 19 is prefer- 20 ably spaced from its adjacent member a distance substantially commensurate with the width of the shank 18 of hook *h* to limit and restrain the hook against sidewise movement, although of course, some clearance be- 25 tween the shank 18 and members 20 is necessary for practical purposes.

The heads 17 may be advantageously formed as shown in Figs. 4, 5 and 6. That is, the upper portion of shank 18 is bent 30 at right angles thereto forming a portion 21 and the end of such portion is coiled concentrically about the shank forming a ring 22 which is closed, or substantially so, and which lies in a plane at right angles to 35 the shank 18. The diameter of ring 22 is substantially that of the sockets 16 and the ring lies partially in the end of one socket and partially in the end of the other socket with the shank 18 disposed between these

40 sockets, free to swing up and down in the slot 19. Thus, the hooks *h* may not only swing out of the case in the desired arc-like path but they are also always free to turn or swivel about an axis at right angles to that about which they are adapted to swing. 45

The hooks *h* may be variously constructed to receive and removably support keys *k* or other similar articles and this invention is independent of the particular style of hook used although the particular form shown in 50 Fig. 5 has been found particularly advantageous and desirable.

The invention has been disclosed herein, in an embodiment at present preferred, for 55 illustrative purposes but the scope of the invention is defined by the appended claims rather than by the foregoing description.

What I claim is:

1. A swivelling hook for key cases and the like, the shank of which has a portion 60 bent into the form of a circle with the axis of the latter disposed in substantially parallel relation with the shank.

2. A swivelling hook for key cases and the like, the shank of which has a portion 65 bent at substantially right angles thereto and then coiled into ring form, the axis of said ring disposed in substantially parallel and concentric relation with the body of the shank.

3. A swivelling hook for key cases and the like, the shank of which has a portion 70 bent into the form of a circle with the axis of the latter disposed in substantially parallel and concentric relation with the shank. 75

In testimony whereof I have affixed my signature.

WARNER R. BUXTON.
